UNITED STATES PATENT OFFICE.

FRANK A. DECKER, OF PHILADELPHIA, PENNSYLVANIA, ASSIGNOR, BY MESNE ASSIGNMENTS, TO DECKER ELECTRICAL MANUFACTURING COMPANY, OF WILMINGTON, DELAWARE.

BATTERY.

No. 880,196.

Specification of Letters Patent.

Patented Feb. 25, 1908.

Application filed March 21, 1904. Serial No. 199,304.

To all whom it may concern:

Be it known that I, FRANK A. DECKER, a citizen of the United States, residing at Philadelphia, in the county of Philadelphia and State of Pennsylvania, have invented certain Improvements in Batteries, of which the following is a specification.

This invention is designed primarily to provide an improved fluid distribution and drainage apparatus for batteries, by which the several compartments may be filled or emptied by conduits communicating therewith through a channeled lid or base coupled into the system by fluid proof connections.

A leading object of the invention is to provide improved means for coupling the parts of the system together.

The nature and characteristic features of the improvements will more fully appear by reference to the following description and the accompanying drawings in illustration thereof, of which:

Figure 1 represents a top plan view of a form of the invention; Fig. 2 represents a sectional view taken on the line 2—2 of Fig. 1; Fig. 3 represents a sectional view of the lid taken on the line 3—3 of Fig. 1; Fig. 4 represents a sectional view of the top of a jar adapted for receiving the lid and couplings; Fig. 5 represents a vertical sectional view of the bottom of a cell having the invention applied thereto; Fig. 6 represents a bottom plan view of the construction shown in Fig. 5; Fig. 7 represents a vertical sectional view of a modification of the coupling shown in Fig. 5; Fig. 8 represents a perspective view of a construction adapted for use either as a base or lid; Figs. 9 and 10 represent sections through modified conduits having means for coupling them together; Fig. 11 represents a top plan view and Fig. 12 a sectional view of the coupling shown in Fig. 10; and Fig. 13 represents a sectional view of fluid passages and couplings for connecting groups of cells.

As shown in Figs. 1 to 4 of the drawings, the jars 1, provided with the cups 2 forming the compartments 3, have the lid 4 which fits within and closes their tops. The lid 5 has the parallel legs 5 containing the insulating conduits 6 and 6^a (suitably of porcelain); the legs having the notches 7 which engage and hold together the walls 1^a cut down below the general level of the tops of the jars. Each of the cells thus formed is pro-

vided with a tube 8 set in the lid 4 and having a port or ports 8' communicating with the conduit 6; each tube being provided with a horizontal member 8^a passing through the bottoms of the cups 2 and having ports 8^b which communicate with the interiors of the cups through the ports 3^a thereof. Each of the cells is also provided with a tube 9 set in the lid 4 and having like communication with the conduit 6^a; each tube having a horizontal member 9^a provided with ports 9^b communicating with the compartments 3. The tops of the respective tubes are fitted with binding nuts 8^d and 9^d adapted for the connection of wires for carrying the current. The conduits 6 and 6^a are connected at their opposite ends with the respective conduits 10 and 10^a, suitably of lead. The lid conduits and the conduits leading thereto are connected by providing the former with sockets as 11 and the latter with branches as 12, which fit in the sockets. The branches are firmly held in the sockets and a fluid proof joint formed by placing externally threaded sleeve nuts 13 on the branches and providing the latter with the flanges 12^a which are jammed in the sockets to form gaskets for the joint by screwing the nuts into the sockets. The jars are provided with the notches 14 which receive the couplings and permit the lid to snugly fit in their tops.

As shown in Figs. 5 to 7, the jar 15 may be supported upon the disconnected rectangular legs 16, respectively provided with insulating conduits as 17, the conduits being connected with the respective conduits 18 for charging and emptying the respective cells and compartments.

As shown in Figs. 5 and 6, each leg 16 is provided with a socket 19 having the shoulder 19^a, the socket providing a passage through the base intersecting the conduit 17. The material, as lead, of which the jar 15 is made, is drawn through the top of the socket so as to form the flange or gasket 20, which is jammed against the shoulder 19^a by the hollow internally threaded nut or plug 21, the latter engaging the threaded end of a tube 22 having a flange 22^a in engagement with and clamping the bottom of the cell. The hollow plug has the passage 21^a affording communication between the conduit 17 and the tube 22. It will be understood that tubes, as 22, are related to the several cups and

compartments of the battery as are the members 8^a and 9^a of Fig. 2.

As shown in Fig. 7, a jar 15 may be connected with the leg 16, by means of a gasket 23 (of lead or rubber) having a flange 23^a engaging the jar and a flange 23^b engaging the shoulder 19^a, a tube 24 having a flange 24^a which engages the gasket flange 23^a, and the hollow plug 21 which has a screw threaded connection with the tube 24 and jams the gasket flange 23^b against the shoulder 19^a of the socket 19.

As shown in Fig. 8, an integral construction may be used, as a part of the supplying and drainage system, which is adapted for either a base or lid, having the plate 25 connecting the channeled legs as 26 provided with sockets as 27, the channels having the passages 28 adapted for communication with tubes extending into a jar.

As shown in Figs. 9 to 12, the system may have the insulating conduits 29 with the threaded sockets 30 connected together by a coupling consisting of the tube 31 having the externally threaded sleeve nuts 32 thereon, the tube then having the flanges 31^a formed thereon and jammed in the sockets 30 as gaskets by screwing the nuts 32 therein. A fluid proof joint is thus formed where two insulating conduits are required to be joined together.

As shown in Fig. 13, where groups of cells are required to be connected together in a common distribution system, an insulating cross 33 may be employed, having the several communicating conduits 34 each connected with a socket 35. A tube 36, (preferably of lead) carrying the externally threaded sleeve nut 37, has the flange 36^a formed thereon and jammed in the socket 35 to form gaskets by screwing the nut 37 therein. The tube is provided with the branches 38 having the flanges 39 with the sleeve nuts 40 thereon for making couplings with insulating channels.

Having described my invention, I claim:—

1. The combination of a conduit, a socket intersecting said conduit, a tube extending into said socket, and a nut engaging said tube

and having a passage therein through which said tube and conduit communicate, substantially as specified. 50

2. The combination of a conduit, a socket intersecting said conduit, said socket having a shoulder, a tube communicating with said conduit, and means in said socket supported by said shoulder and engaging said tube, substantially as specified. 55

3. The combination of a cell, with a conduit, a shouldered socket intersecting said conduit, a tube communicating with said cell and extending into said socket, and a hollow nut engaging said tube and supported by said shoulder in said socket, substantially as specified. 60

4. The combination of a cell, with a conduit, a shouldered socket intersecting said conduit, a tube connecting said cell and socket, a gasket surrounding said tube, and a hollow nut engaging said tube and jamming said gasket against said shoulder, substantially as specified. 65

5. A cell, in combination with an insulating leg having a passage therethrough, a socket intersecting said passage and a tube seated in said socket and communicating with said cell, substantially as specified. 70

6. A cell having compartments therein, a plurality of insulating legs, a conduit in each of said legs, and means for connecting each of said conduits with one or more compartments of said cell, substantially as specified. 80

7. A cell having compartments therein, a pair of insulating legs connected by an insulating plate, a conduit in each of said legs, and means for connecting each of said conduits with one or more compartments of said cell, substantially as specified. 85

In testimony whereof I have hereunto set my hand this 18th day of March, one thousand nine hundred and four, in the presence of the subscribing witnesses. 90

FRANK A. DECKER.

In presence of—

THOMAS S. GATES,
UTLEY E. CRANE, Jr.
